UNITED STATES PATENT OFFICE

140,590

DESIGN FOR A TOY STORAGE CHEST

Henry P. Glass, Chicago, Ill.

Application November 13, 1944, Serial No. 116,302

Term of patent 7 years

(Cl. D33—19)

To all whom it may concern:

Be it known that I, Henry P. Glass, a citizen of the United States, residing at Chicago, in the county of Cook and State of Illinois, have invented a new, original, and ornamental Design for Toy Storage Chests, of which the following is a specification, reference being had to the accompanying drawing, forming part thereof.

Fig. 1 is a front elevational view of a toy storage chest, showing my new design;

Fig. 2 is a right-hand side elevational view;

Fig. 3 is a left-hand frontal perspective view with the drawers open in one direction; and

Fig. 4 is a right-hand similar view with the drawers open in another direction.

I claim:

The ornamental design for a toy storage chest, as shown.

HENRY P. GLASS.
